United States Patent Office

Des. 228,400
Patented Sept. 18, 1973

228,400

JUVENILE RIDING VEHICLE

Stanley Martin Novak, Jr., Olney, Ill., assignor to
AMF Incorporated

Filed Feb. 25, 1972, Ser. No. 229,617

Term of patent 14 years

Int. Cl. D21—01

U.S. Cl. D34—15 AJ

FIG. 1

FIG. 2

FIG. 3

FIG. 4

FIG. 5

FIG. 1 is a top plan view of a juvenile riding vehicle showing my new design;

FIG. 2 is a right side elevational view thereof, the left side being a mirror image thereto;

FIG. 3 is a bottom plan view thereof;

FIG. 4 is a front elevational view thereof;

FIG. 5 is a rear elevational view thereof.

I claim:

The ornamental design for a juvenile riding vehicle, substantially as shown and described.
